DISK DISPENSER

Albert I. Negus, Jr., Madison, Wis.

Application May 13, 1946, Serial No. 669,412

1 Claim. (Cl. 312—61)

The present invention relates generally to improvements in the art of storing and dispensing, and relates more particularly to improvements in the construction and operation of devices for dispensing filter or sediment disks.

A primary object of my present invention is to provide a new and useful filter disk dispensing unit which is simple and durable in construction and highly efficient and sanitary in use.

In the dairy industry, it is customary practice to test the sediment in milk by passing quantities of the milk through cotton filter disks or the like commonly called milk sediment disks, thereafter examining the disks to analyze the sediment deposit thereon. Accordingly, disks manufactured especially for this purpose are available to the industry, such disks being usually sold in lots and of standard size packages in cardboard confining cartons or the like. In use, it has heretofore been common practice in dairies or the like to open one or more of the confining cartons and empty the contents or a portion thereof on a table or other convenient place for periodic use, leaving filter disks scattered about in an untidy and unsanitary manner for varying periods of time and likewise resulting in lossage of some of the disks.

It is therefore a more specific object of this invention to provide an improved filter disk dispenser, which besides being relatively simple, compact and durable in construction, is adapted to be quickly and easily filled and assembled by a novice for housing a relatively large quantity of sediment disks in neat and sanitary condition.

Another specific object of my invention is to provide an improved filter disk dispenser which may be readily loaded by merely inserting the loading element or cartridge thereof longitudinally within the disk confining carton in which the disks are merchandised and thereafter inserting the disk laden cartridge within the main casing or housing of the dispenser.

Another specific object of the present invention is to provide an improved unit for confining filter disks which may be conveniently located and from which single disks may be easily removed by simple finger operation.

A further specific object of the present invention is to provide an improved confining and dispensing unit for filter disks wherein the confined disks are automatically and continuously fed to the dispensing slot as disks are removed therefrom.

An additional specific object of the invention is to provide an improved filter disk dispenser which may be readily manufactured of sheet metal at relatively low cost with the aid of punches and dies.

Still another specific object of this invention is to provide an improved filter dispenser and

method of loading the same in a simple and time-saving manner.

These and other specific objects and advantages of the invention will be apparent from the following detailed description.

A clear conception of the features constituting my present improvement, and of the mode of constructing and of operating and method of loading filter disk dispensers built in accordance with the invention, may be had by referring to the drawing accompanying and forming a part of this specification wherein like reference characters designate the same or similar parts in the several views.

15 Fig. 1 is a side view of the loading element of the dispensing unit, showing the same inserted longitudinally within a disk confining carton, the latter being shown in section;

20 Fig. 2 is a partial section through several of the elements of the unit, showing the disk laden loading element being inserted within the main casing or disk confining element;

25 Fig. 3 is a side elevation of the dispensing unit in condition for normal operation and showing the disk lowering weight in action;

30 Fig. 4 is a transverse section through Fig. 1 taken on the line 4—4; and

Fig. 5 is a transverse section through Fig. 3 taken along the line 5—5.

35 While the invention has been shown and described herein as being specifically embodied in a housing and dispensing unit for cotton filter disks as commonly used in pressure sediment testers, it is not my desire or intention to thereby unnecessarily restrict or limit the utility of the improved dispenser.

Referring to the drawing, the improved filter disk dispenser shown therein, comprises in general, an elongated casing or housing 10 having a substantially U-shaped cross-section and provided with oppositely directed side flanges 11; a mounting plate 12 having turned in edges 13 forming grooves adapted for cooperation with the flanges 11 of the casing 10, the mounting plate 12 being formed of sheet-metal and secured in any suitable manner, as by screws 14, to a supporting bracket 15 or the like; and a loading element or cartridge 16 having an end cover plate 17 and a rear wall 18 and side walls 19 forming a trough for the reception of cotton disks 20 or the like and a sliding weight 21, the edges of the side walls 19 being bent inwardly toward each other at 22 to cooperate with grooves 23 formed in the weight 21 to permit sliding movement thereof.

The disk receiving trough of the loading cartridge 16 should be of such width that it may be loaded by longitudinal insertion within a confining carton 24 such as the disks 20 are commonly merchandised in, as shown in Figs. 1 and

4; and after loading of the cartridge 16, it is insertible longitudinally within the casing 10, one end of which is open at 25 and adapted to be closed by the cover 17 of the cartridge 16 while the opposite end has a pair of downwardly and outwardly directed prongs 26 spaced apart to form a finger slot 27, as shown in Figs. 2, 3 and 5, for removing the disks 20. The cover plate 17 of the cartridge 16 is preferably provided with a spring clip 28 adapted to coat with the inner wall of the casing 10, and clearly shown in Fig. 3, to retain the cartridge 16 in position within its housing, and the lower ends of the inturned edges 13 of the mounting plate 12 are pinched at 29, thereby providing a stop for the flanges 11 of the casing 10 when inserted vertically within the plate 12. The casing 10, mounting plate 12 and cartridge 16 may all be readily formed separately of sheet metal with the aid of punches and dies, and the weight 21 may be formed in any convenient manner and should be of sufficient heft to compress the disks 20 and constantly urge the same downwardly toward the dispensing slot 30 between the prongs 26 and the main body of the casing 10 when the unit is loaded and assembled in operative position as in Fig. 3.

To load and assemble the improved sanitary dispenser, the casing 10 is first removed from the mounting plate 12 in an obvious manner by vertical upward movement and the cartridge 16 is similarly removed from within its housing 10. The end flap 31 of the disk confining merchandizing carton 24 is then opened; and with the weight 21 at the end adjacent the cover plate 17, the loading trough of the cartridge 16 is inserted longitudinally within the carton 24, as shown in Fig. 1, with the walls 18, 19 of the trough sliding between the adjacent inner side walls of the carton and the disks 20 confined therein. With the trough of the cartridge 16 inserted in this manner approximately the full length of the carton 24, the heretofore closed end flap 32 may be opened and pressure exerted in any convenient manner, as by a finger, upon the end disks to urge the disks 24 toward the cover end of the cartridge 16 during longitudinal removal of the cartridge. With the cartridge 16 thus loaded with the flat disks 20, the disk-laden trough is next inserted longitudinally within the casing 10 through its open end 25 until the cover 17 closes the end 25 with the spring 28 coating with the wall of the casing 10. Finally, the casing 10, housing the cartridge 16, disks 20 and weight 21, is mounted for operation on the plate 12 by inserting the flanges 11 of the casing vertically downward within the cooperating grooves formed by the inturned edges 13 of the mounting plate.

With the dispenser thus loaded and assembled, the weight 21, with its grooves 23 cooperating with the inturned edges 22 of the cartridge trough, constantly compresses and urges the disks 20 downwardly toward the lower dispensing slot 30 from which they may be removed one at a time in an obvious manner by merely placing a finger in the slot 27 against the lower surface of the bottom disk and pulling the disk through the downwardly and outwardly directed dispensing slot 30. Obviously, as each bottom disk is removed, another disk is automatically lowered into position against the prongs 26 by reason of the action of the weight 21, and when all of the disks 20 have been exhausted from within the housing

10, the unit may be readily refilled as hereinabove described.

From the foregoing detailed description, it will be apparent that my present invention provides an improved dispenser for flat articles such as filter disks which is simple, compact and durable in construction, and which may be readily loaded with the articles to be dispensed in a novel and convenient manner. The dispensing assemblage 10 may be conveniently located for ready access by either securing the mounting plate 12 to a portable bracket or supporting member or directly to the wall or article of furniture in the dairy. The various parts may be economically manufactured of sheet metal or the like and may be rapidly assembled by a novice to provide a sanitary dispensing receptacle. With the improved dispenser, a relatively large number of disks may be neatly confined for ready use, and the weight 21 assures automatic feeding of the disks to the dispensing slot 30. The casing 10 and cartridge 16 may be made of various lengths to accommodate one or more cartons of disks of any standard size, and dispensers embodying the invention have proven highly efficient and satisfactory in actual use.

It should be understood that it is not desired or intended to limit this invention to the exact details of construction, or to the precise method of loading or mode of use and operation, herein shown and described, for various modifications within the scope of the appended claims, may occur to persons skilled in the art to which this invention pertains; and the term "filter disk" as used herein is meant to include similar articles adapted to be stacked in a like manner.

I claim:

A filter disk dispenser comprising, a casing having dispensing and finger slots at one end thereof, means for supporting said casing in approximately upright position with said slots at the lower casing end, means forming a trough insertable within and removable from said casing for loading the same with filter disks, the side walls of said trough having inturned edges, and a weight having grooves cooperable with the inturned edges of said trough for guiding movement of said weight within said trough whereby said weight is adapted to constantly urge the disks housed within said casing toward said dispensing slot.
